UNITED STATES PATENT OFFICE

LOUIS A. HAZELTINE, OF HOBOKEN, NEW JERSEY, ASSIGNOR TO HAZELTINE CORPORATION, A CORPORATION OF DELAWARE

RADIO RECEIVING SYSTEM

Original application filed February 27, 1925, Serial No. 12,000, now Patent No. 1,648,808, dated November 8, 1927. Divided and this application filed October 24, 1925. Serial No. 64,533.

This invention relates to wave signaling systems, particularly to regenerative or heterodyne radio receiving systems, and has for its object the prevention of radiation of locally generated oscillations especially from the antenna of such receiving systems.

Oscillating or regenerative receiving systems, with consequent radiation therefrom, have been the cause of serious interference with satisfactory reception by other receivers in the neighborhood. This type of interference has become so acute in certain densely populated portions of the United States as to render satisfactory broadcast reception impossible.

The invention described in the present application, which is a division of my copending application Serial No. 12,000, filed February 27, 1925, issued November 8, 1927, as Patent No. 1,648,808, provides extremely simple but adequate means for preventing undesirable radiation of locally produced oscillations, and at the same time provides a radio-frequency amplifier which increases the sensitivity and selectivity of the receiving system in which it is incorporated.

These results are accomplished by interposition between the antenna system and the local radio-frequency oscillatory source, of a tuned radio-frequency vacuum tube amplifier, in one or more stages, with complete elimination of coupling between anode and control grid circuits of the tubes, except through the mutual conductance thereof on which the amplifier action depends.

The effective elimination of coupling between the anode circuits and the grid circuits is accomplished by the cooperation of three steps: First, the arrangement of the amplifier transformers so that there is no magnetic coupling between any two of them; second, the avoidance in the wiring of any substantial impedance common to two or more tuned circuits; and third, the neutralization of the natural capacity coupling inherent between the tuned circuits, including particularly that due to the capacity between the grid and the anode of the vacuum tube.

The elimination of undesirable coupling between anode and grid circuits of the vac-

uum tube, results in prevention of retroaction or regenerative feedback within the amplifier, and also serves effectively to localize oscillations of the source in the output portion of the amplifier, and to prevent their being communicated to the antenna system to be radiated therefrom.

The single figure of the drawing illustrates diagrammatically an extremely simple embodiment of the present invention as applied to radio receiving systems.

The receiver shown comprises two vacuum tubes, A₁ and D, the first of which functions in a neutralized tuned radio-frequency amplifying stage, and the second comprises the customary detector or rectifying tube, which is here made regenerative or continuously oscillating by tuning the anode circuit with a variable inductance L. Such an arrangement is particularly suitable for radio reception of unmodulated continuous-wave signals by the heterodyne method, and, as outlined above, has the advantage over the usual regenerative receiver that the oscillations produced by the detector tube are not communicated to the antenna, where they would cause objectionable radiation. Another useful application of this device is in the reception of damped or modulated waves, wherein, by causing the detector to oscillate, the carrier waves of an unknown station may be "picked up" by the well-known beat method.

Referring to the drawing, the radio-frequency signaling system comprises a current collecting device or antenna A and ground G tapped to a coil Ta having in shunt thereto a variable condenser Ca for adjusting the system selectively to receive signals throughout a range in frequency. Vacuum tube A₁, operating as an amplifier, is arranged with control grid G₁ and filament or cathode K₁ connected to the tuned input portion Ta—Ca for transferring signals therefrom through the cathode K₁ and an anode or output electrode O₁ of tube A₁ to the succeeding or output system.

The output system includes a transformer T₁ tunable as a unit to the selected frequency by variable condenser C₁ in shunt to the secondary winding L_s of the transformer. In

this manner the signals are impressed between cathode K_2 and control grid G_2 of tube D which functions as a detector due to the interposition of a grid-condenser and leak-resistance M in series with the control grid G_2 .

Additionally tube D becomes a radio-frequency oscillatory source providing optionally regenerative or heterodyne detection by virtue of the cooperant action of variable inductance L, included in circuit between cathode K_2 and anode O_2 of the tube, and the inherent capacity C_o existing between anode O_2 and control grid G_2 , which cause the output portion of the tube to react in aiding phase upon its input portion thereby producing or tending to produce oscillation.

The received signals are rendered audible by headphones H so arranged in the output portion of tube D as to be traversed by the rectified signals, the high-frequency components being by-passed by condenser C_b .

The usual potential supply sources B_A and B_B are connected to energize the cathode and anode circuits of the tubes A₁ and D in common. The cathode or filament current is controlled by interposed rheostat R. With the single stage of radio-frequency amplification shown, sufficient negative bias for the control grid G_1 of the amplifier tube A₁ is obtained by merely connecting it to the negative side of the cathode as shown in the drawing. With a larger number of stages it would be necessary to provide additional negative bias for the control grids of the amplifier tubes as disclosed more particularly in my mentioned patent, especially in Figs. 5a and 6 thereof and accompanying description.

The localization of the oscillations in the detector tube is accomplished by elimination of undesirable couplings between the grid and plate circuits of vacuum tube A₁, largely through the use of neutralizing condenser C_n in combination with a portion L_n of secondary coil L_s closely coupled to the primary winding L_p of transformer T₁. Coupling between the anode and grid circuits of tube A₁ due to the natural capacity C_o between the anode and grid electrodes, together with apparatus associated therewith, is neutralized by the neutralizing capacity C_n connected between the control grid and the portion L_n of the secondary winding L_s of transformer T₁. This auxiliary coil L_n, or neutralizing winding, is, in this example, that portion of the secondary winding of transformer T₁ which is included between the tap 1 and the low-potential end 2 of the secondary winding.

As explained in my U. S. Letters Patent Nos. 1,489,228 and 1,533,858, neutralization of the undesirable capacity coupling will be effected when the primary winding L_p of transformer T₁, and the neutralizing wind-

ing L_n thereof, are closely coupled electro-magnetically, and so arranged with relation to each other that the corresponding terminals (as 1 and 1', or 2 and 2') of the respective windings are of opposite polarity, the ratio of the number of turns of the neutralizing winding L_n to the number of turns of the primary winding L_p being equal to the ratio of the value of the undesirable coupling capacity C_o to that of the neutralizing capacity C_n.

With the capacitive coupling between control grid and anode thus neutralized, any residual couplings occurring between input and output portions of the amplifier may be eliminated to any required degree of refinement by employment of one or more of the various expedients disclosed in my parent application, now Patent No. 1,648,808. For example, magnetic coupling between any two transformers such as T₁ and T₂ may be eliminated by mounting them with their axes parallel and at an angle of substantially 55 degrees with the line of centers, as more fully described in my Patent No. 1,577,421 issued March 16, 1926. Residual capacitive as well as magnetic couplings may be eliminated by use of suitable shielding. By-pass condensers may be utilized to provide low-impedance return paths for the radio-frequency grid and anode circuits directly to their respective cathodes, thus eliminating couplings due to the use of common potential-supply sources and the like. As stated in my mentioned Patent No. 1,648,808, the requisite refinements in elimination of couplings increase with the number of amplifier stages employed.

In order to simplify the disclosure, the embodiment of the present invention as described is shown as including but one neutralized tuned radio-frequency amplification stage. It is obvious, however, that the fundamental arrangement illustrated herein may with great success be enlarged to include two or more stages of tuned radio-frequency amplification, the vacuum-tube coupling capacity in each stage being neutralized according to the method herein described. Again, any of the vacuum tubes utilized for radio-frequency amplification, except the tube coupled directly to the antenna, may be arranged to be regenerative, instead of, or in addition to, the detector tube.

A particularly effective radio receiver for broadcast reception may include two stages of neutralized tuned radio-frequency amplification, a regenerative detector, and two stages of audio-frequency amplification. If the tuned radio-frequency amplifier be designed for maximum radio-frequency amplification, no great increase in amplification or selectivity will be noted through the employment of regenerative action in the detector. However, it is at times convenient to use a

regenerative detector so that unknown transmitting stations may be tuned in by means of the well-known heterodyne or beat reception method. The radio receiver herein provided may thus include a regenerative detector, or other source of oscillation, and at the same time be incapable of radiating energy which is likely to interfere with other radio reception in the vicinity.

It is to be noted that, while the means illustrated for causing the detector to become regenerative, or oscillating, comprises a variable tuning inductance L inserted in the plate or anode circuit of vacuum tube D, whereby energy in the anode circuit will be fed back into the grid circuit through the inherent grid-anode electrostatic capacity of the tube, other well-known methods for facilitating and controlling the transfer of energy from the output circuit to the input circuit of a vacuum tube may likewise be employed. For example, the inductance L could be electromagnetically coupled to the secondary winding of transformer T₁, and thereby function as an electromagnetic feed-back or tickler coil. Other known methods which may likewise be used to obtain regenerative reactions may comprise coupling the output circuit to the input circuit of the vacuum tube by means of added capacity, self-inductance, or resistance, common to those circuits.

It will be obvious that the present invention may be applied with merit to any receiving system wherein it is desired to prevent oscillations from being radiated from the antenna, regardless of whether such oscillations are continuously generated, as in the super-heterodyne receiving system, or whether they be only occasionally produced, as in the usual regenerative detector.

I claim:

1. In a radio receiver adapted to be connected to an antenna system, a radio-frequency amplifier including at least one vacuum tube having grid and plate electrodes, said grid being included in an input circuit of said amplifier tube and said plate in an output circuit thereof, capacity between said circuits including the natural capacity inherent between said grid and plate electrodes, said circuits being traversed by currents of such high frequency as to make appreciable the capacity coupling between said circuits due to the said capacity and through which coupling high-frequency energy may be transferred to said antenna and radiated therefrom, an additional vacuum tube having an input circuit and an output circuit, said input circuit thereof being linked with said output circuit of said additional tube to facilitate the transfer of energy from said output circuit to said input circuit thereof for producing oscillations, and means associated with said radio-frequency amplifier tube for neutralizing the undesirable capacity

coupling between the input and output circuits thereof, whereby said oscillations are in effect localized in said additional vacuum tube and thereby substantially prevented from being communicated to said antenna system. 70

2. In a radio receiver adapted to be connected to an antenna system, a radio-frequency amplifier including at least one vacuum tube having grid, plate and filament electrodes, said grid being included in an input circuit of said tube, and said plate in an output circuit thereof, capacity between said circuits including the natural capacity inherent between said grid and plate electrodes, 75 said circuits being traversed by currents of such high frequency as to make appreciable the capacity coupling between said circuits due to the said capacity and through which coupling high-frequency energy may be transferred to said antenna and radiated therefrom, a vacuum tube detector having an input circuit and an output circuit, means for coupling the input circuit of said detector to the output circuit of a tube of said radio-frequency amplifier, means in the output circuit of said detector to facilitate the transfer of energy from the output circuit of said detector to the input circuit thereof whereby oscillations may be produced, and means including a capacity and a coil connected in series between the grid and the filament system of a tube of said radio-frequency amplifier for neutralizing the undesirable capacity coupling between the input and output circuits thereof, whereby said radio-frequency amplifier tube is rendered incapable of generating oscillations and whereby oscillations produced by said detector are in effect localized in said detector and thereby substantially prevented from being communicated to said antenna system. 95

3. In a radio receiver adapted to be connected to an antenna, a radio-frequency amplifier including a vacuum tube having grid and plate electrodes, an input circuit and an output circuit, inherent capacity including grid-plate capacity effectively connected between said circuits, said circuits being traversed by currents of such high frequency as to make appreciable the capacity coupling normally existing between said circuits due to said inherent capacity, and through which coupling high-frequency energy may be transferred to said antenna and radiated therefrom, a second vacuum tube having an input circuit and an output circuit, the input circuit of said second vacuum tube being coupled to an output circuit of said amplifier, means connected with said second vacuum tube to facilitate the transfer of energy from the output circuit to the input circuit thereof for producing oscillations, and means associated with said radio-frequency amplifier for neutralizing said capacity coupling 130

whereby said oscillations are in effect localized in said second vacuum tube and are thereby substantially prevented from being communicated to said antenna.

4. In a radio receiver adapted to be connected to an antenna system, a radio-frequency amplifier including a vacuum tube having an input circuit including a grid electrode and an output circuit including a plate electrode, inherent capacity including grid-plate capacity effectively connected between said circuits, said circuits being traversed by currents of such high frequency as to make appreciable the capacity coupling normally existing between said circuits due to said inherent capacity, through which coupling high-frequency energy may be transferred to said antenna system and radiated therefrom and whereby said energy may cause voltage fluctuations to be impressed upon said grid electrode with the generation of resultant undesired oscillations by said radio-frequency amplifier tube, a second vacuum tube having an input circuit and an output circuit, the input circuit of said second vacuum tube being coupled to an output circuit of said amplifier, means connected with said second vacuum tube to facilitate the transfer of energy from the output circuit to the input circuit thereof whereby oscillations are produced, and means associated with said radio-frequency amplifier for neutralizing said capacity coupling whereby said amplifier is rendered incapable of generating oscillations and whereby the oscillations generated by said second vacuum tube are in effect localized in said second tube and are thereby substantially prevented from being communicated to said antenna system.

5. In a radio signaling system including a vacuum tube capable of being placed alternatively in an oscillating and in a non-oscillating condition, a radio-frequency amplifier having an input circuit, an output circuit, and at least one vacuum tube coupled to said first-mentioned vacuum tube and adapted to relay radio-frequency signals thereto, inherent capacity between said input and output circuits, said circuits being traversed by currents of such high frequency as to make appreciable the capacity coupling normally existing between said circuits due to said inherent capacity, through which coupling high-frequency oscillations generated by said first-mentioned vacuum tube may be returned in a direction opposite to that in which said signals are relayed, and means associated with said radio-frequency amplifier for neutralizing said capacity coupling whereby said amplifier is adapted to transfer high-frequency energy substantially in one direction only, and consequently whereby said oscillations are in effect localized in said first-mentioned vacuum tube.

6. In a radio signaling system adapted to be connected to an antenna system, a detecting means alternatively operable as a non-oscillating detector and as a heterodyning detector, a radio-frequency vacuum tube amplifier having an input circuit including a grid electrode, and an output circuit including a plate electrode, said amplifier being coupled between said antenna system and said detecting means, inherent capacity including grid-plate capacity between said input circuit and said output circuit, said circuits being traversed by currents of such high-frequency as to make appreciable the capacity coupling normally existing between said circuits due to said inherent capacity, through which coupling high-frequency oscillations generated by said heterodyning detector may be transferred to said antenna system and radiated therefrom, and means associated with said radio-frequency amplifying tube for neutralizing said capacity coupling, whereby said oscillations are in effect localized in said detecting means and are thereby substantially prevented from being communicated to said antenna system.

7. The combination in a radio-frequency signaling system of a vacuum tube arranged with a control grid and a cathode connected to an input portion for transferring signals through said cathode and an output electrode of said tube to an output system which includes a radio-frequency oscillatory source, of means preventing potential variations occurring between said output electrode and cathode from reacting upon said input portion, whereby oscillations of said source are in effect localized in said output system and thereby prevented from being communicated to said input portion.

8. The combination in a radio-frequency signaling system of a vacuum tube arranged with a control grid and a cathode connected to an input portion for transferring signals through said cathode and an output electrode of said tube to an output system which includes a radio-frequency oscillatory source, of means diverting from said input portion retroactive currents originating in succeeding portions of said system, whereby oscillation current of said source is effectively localized in said output system and prevented from being communicated to said input portion.

9. The combination in a radio-frequency signaling system adjustable selectively to receive signals throughout a range in frequency and including an input portion adapted for connection to an antenna, a vacuum tube having control grid and a cathode connected to said input portion, and an output electrode and said cathode connected to an output system which includes a radio-frequency oscillatory source, of means preventing poten-

tial variations occurring between said output electrode and cathode from reacting upon said input portion, whereby oscillations of said source are in effect localized in said output system and thereby prevented from being communicated to said antenna.

10. The combination in a radio-frequency signaling system adjustable selectively to receive signals throughout a range in frequency and including an input portion adapted for connection to an antenna, a vacuum tube having a control grid and a cathode connected to said input portion, and an output electrode and said cathode connected to an output system which includes a radio-frequency oscillatory source, of means diverting from said input portion retroactive currents originating in succeeding portions of said system, whereby such portions are prevented from reacting upon said input portion, thereby to localize in said output system oscillations of said source and to prevent their being communicated to said antenna.

11. In a radio-frequency signal receiver, the combination of a vacuum tube having a control grid and an anode, an input circuit connected to said grid and adapted to be connected with an antenna, an output system including a radio-frequency oscillation current source coupled to said anode and causing undesirable capacity currents to flow from said anode to other parts within said tube, and means substantially independent of frequency causing said capacity currents to flow back to said output circuit without traversing said input circuit, whereby oscillation current of said source is effectively localized in said output circuit and thereby prevented from being communicated to said antenna.

12. In a radio-frequency signal receiver, the combination of a vacuum tube having a control grid and an anode, an input circuit connected to said grid and adapted to be connected with an antenna, an output circuit including a radio-frequency oscillation current source coupled to said anode and causing undesirable capacity currents to flow from said anode to other parts within said tube, and means independent of frequency diverting said capacity currents away from said input circuit, whereby oscillation current of said source is effectively localized in said output circuit and thereby prevented from being communicated to said antenna.

13. In a radio receiver, the combination with an antenna and a radio-frequency oscillatory source, of a unidirectional repeater located between said antenna and said oscillatory source for transferring signals from said antenna thereto, said uni-directional repeater comprising the combination of a vacuum tube with means for preventing effects upon the input circuit terminals of variations in potential across the output circuit terminals

due to coupling otherwise present within said tube, and means for reducing incidental coupling between elements in the input and output circuits of said tube.

14. In a radio receiver, the combination with an antenna and a radio-frequency oscillatory source, of a unidirectional amplifier stage comprising a vacuum tube having a control grid, cathode and anode, circuit elements providing an input and an output circuit for said stage, means coupling said input circuit to said antenna, means for tuning one of said circuits to resonance at a desired frequency, means preventing the varying potential of said output circuit from acting through coupling otherwise present within said tube from establishing variations of potential across said input circuit, and means for shielding the elements of said input and output circuits to prevent incidental couplings to and between the same.

15. The combination in a radio-frequency signaling system adjustable selectively to receive signals throughout a range in frequency and including an input portion adapted for connection to an antenna, a vacuum tube having a control grid and a cathode connected to said input portion, and an output electrode and said cathode connected to an output system which includes a radio-frequency oscillatory source, of means eliminating retroactive coupling between said output system and said antenna, whereby oscillations of said source are effectively localized in said output system and thereby prevented from being communicated to said antenna.

16. The combination in a radio-frequency signaling system of a vacuum tube arranged with a control grid and a cathode connected to an input circuit for transferring signals through said cathode and an anode of said tube to an output circuit which includes a radio-frequency oscillatory source, inherent capacity including grid-anode capacity effectively connected between said circuits, of means associated with said tube for neutralizing said capacity coupling, whereby oscillations of said source are effectively localized in said output circuit and thereby prevented from being communicated to said input circuit.

In testimony whereof I affix my signature.
LOUIS A. HAZELTINE.
